PACKAGE

Walter E. Wilson, Detroit, Mich.

Application April 8, 1933, Serial No. 665,049

9 Claims. (Cl. 41—4)

My invention relates to a package and more particularly to an improved package adapted for use in connection with the packaging of merchandise contained in bottles, such as inks, show-
5 card colors, etc. It is particularly adaptable to any package in which it is desired to maintain a plurality of bottles in the package in an upright position in a manner to permit ready access to the contents of the bottle without removal of the 10 bottle from the package.

In the particular embodiment here shown my invention is shown as applied to a child's paint set in which a number of liquid colors are placed in a plurality of bottles which are maintained 15 in the package embodying my invention.

The sale of merchandise in small bottles is highly desirable in a large number of classes of merchandise. Frequently, also, it is desirable to sell a plurality of such bottles in a single pack-
20 age. Prior to my invention such packages have not been desirable from the standpoint of the customer or user of the merchandise contained in the bottles, because of the difficulty of removing the stoppers from the bottles and the 25 maintaining of the bottles in an upright position.

It also has been found with such merchandise, particularly with children's paint sets in which liquid colors are sold in a plurality of small bot-
30 ties, that it is difficult to maintain the bottles in an upright position during use due, many times, to the unevenness of the surface upon which the bottles are to be used and due also to the relative smallness of the bottoms of the bottles com-
35 monly employed in sets of this type.

It is, therefore, an object of my present invention to provide a package particularly adapted for the packaging of merchandise contained in a plurality of bottles and in which the bottles are se-
40 curely held in an upright position at all times.

It is a further object of my present invention to provide a package in which a plurality of bottles are so held in an upright position that the stoppers or caps thereof may be removed with-
45 out removing the bottles from the package and without requiring a manual holding of the bot-
tles.

These and various other objects, features of ar-
50 rangement, construction and operation, are plainly shown and described and will be best understood by reference to the accompanying drawing, in which:

Fig. 1 is a top plan view with a portion of the cover broken away showing a package em-

bodying my invention adapted for use as a paint set;

Fig. 2 is a staggered sectional view taken on the line 2—2 of Fig. 1;

Fig. 3 is an enlarged fragmentary sectional view taken on the line 3—3 of Fig. 1.

Similar reference numerals refer to similar parts throughout the several views.

Referring more in detail to the drawing, 10 designates the bottom portion of a box of conventional design on which is placed a telescoping cover 11, also of conventional design. A plurality of bottles 12 contain the merchandise to be sold. The depth of the box 10 is proportioned to the height of the bottles 12 in such a manner 15 that when the telescoping cover portion 11 is in place to close the box, it contacts with the top of the plurality of caps 13 secured to the plurality of bottles 12 (Figs. 2 and 3).

Placed in the bottom portion 10 of the box is a 20 partition 14. A plurality of openings of suitable size and shape corresponding to the size and shape of the bottles 12 to be contained therein is provided in the partition 14. Each of the plurality of bottles 12 is provided with locking means 15 and 25 16 formed as an integral part of the bottle 12. The openings in the partition 14 are so arranged that the partition 14 extends to the surface of the bottle 12 at a point between the locking means 15 and the locking means 16 integral with the 30 body of the bottles 12.

In the particular adaptation here shown, a plu-
35 rality of pins 17 also are provided and are pressed through suitable openings in the partition mem-
ber 14.

In assembling a package embodying my inven-
40 tion, each of the bottles 12 is filled with the mer-
chandise to be sold therein and is then forced
through the openings in the partition 14 with a
distortion of the partition 14. The partition 14
is formed preferably of cardboard or similar ma-
45 terial so that it will yield slightly as the locking
means 16 is forced downwardly through the
opening provided in the partition 14. The ma-
terial employed to form the partition 14 should
be of sufficient resiliency to restore itself to its
50 normal position so that the edges of the opening
in the partition 14 will engage the bottle 12 at a
point between the locking means 15 and the lock-
ing means 16.

A package embodying my invention thus makes
55 available to the user the contents of any one of
the plurality of bottles packed therein without
affecting the accessibility of any other bottle in
the package. The construction of the partition

member 14 cooperating with the locking means 15 and 16 serves to maintain the bottles 12 in a pre-determined upright position in the package. By providing a bottle of a shape other than circular 5 as here shown, it is possible to remove any one of the screw caps 13 from any one of the plurality of bottles 12 without turning the bottle in the package and without removal of the bottle from the package.

10 A package embodying my invention also facilitates the shipping of merchandise packed in a plurality of small containers, particularly when arranged in the package as shown in the embodiment of my invention set forth in the drawing 15 and described in this specification. The cover 11, telescoping over the bottom portion 10, contacts with the plurality of caps 13 on the plurality of bottles 12 and serves to prevent loosening of the caps on any of the bottles contained there- 20 in.

While I have illustrated a preferred embodiment of my invention, many modifications may be made without departing from the spirit of the invention, and I do not wish to be limited to the 25 precise details of construction set forth, but desire to avail myself of all changes within the scope of the appended claims.

Having thus described my invention, what I 30 claim is new and desire to secure by Letters Patent of the United States is:

1. A package for a paint set or the like comprising a box having a flat bottom, a spacer partition sheet supported in the box in spaced relation above said bottom and substantially parallel 35 thereto, said sheet having a rectilinear opening therein, a rectilinear bottle adapted to extend through said opening and having opposed vertical sides engaging the opposed side edges of the opening, and parallel horizontal ribs projecting 40 outwardly from said sides and engaging opposite faces of the partition sheet along said edges to resist tilting movement of the bottle when supported within said opening.

2. A package for a paint set or the like comprising a box having a flat bottom, a spacer partition sheet supported in the box in spaced relation above said bottom and substantially parallel thereto, said partition sheet being formed of flexible material and having a rectilinear opening 50 therein, a rectilinear bottle adapted to extend through said opening and having opposed vertical sides engaging the opposed side edges of the opening, and parallel horizontal ribs projecting 55 outwardly from said sides, the said edges of said opening being sprung into interlocked position between said ribs and engaged by said ribs to maintain said bottle against tilting movement when supported within said opening.

60 3. A package for a paint set or the like comprising a box having a flat bottom, a spacer partition sheet supported in the box in spaced relation above said bottom and substantially parallel thereto, said partition sheet being formed of flexible material and having a rectilinear opening 65 therein, a rectilinear bottle adapted to extend through said opening and having opposed vertical sides engaging the opposed side edges of the opening, and parallel horizontal ribs projecting outwardly from said sides, the said edges of said opening being sprung into interlocked position 70 between said ribs by movement of the bottle in a substantially vertical direction relative to the partition and engaged by said ribs to maintain

said bottle against tilting movement when supported within said opening.

4. A package adapted for a paint set or the like and including a plurality of rectilinear bottles maintained in upright position in a box, each of said bottles having opposite vertically extending sides, a plurality of outwardly extending spaced ribs formed integrally with the sides of each of said bottles and extending outwardly from the surfaces of said sides on lines substantially parallel with a line extending through the bottom of the bottle at a point approximating the center of gravity thereof. 80

5. A package adapted for a paint set or the like and including a plurality of bottles adapted to contain liquid paints, a box, a spacer partition therein, each of said bottles having a plurality of spaced parallel ribs extending outwardly from the sides thereof on lines extending through the approximate center of gravity thereof and adapted 85 to be interlocked with said spacer partition and to cooperate therewith to maintain each of the bottles in upright position and against tilting movement in said box. 90

6. A paint set including a plurality of rectilinear bottles containing different colors of liquid paints, a box, a spaced partition formed of a sheet of flexible material having a plurality of spaced rectilinear openings therein and secured to said box in spaced relation to the bottom thereof, each of said bottles having outwardly extending flanges integral with the sides thereof at the approximate center of gravity thereof and adapted to be sprung into interlocked position in the openings in said partition and to engage the 100 opposite faces of said partition at said openings, thereby to maintain each of said bottles against 105 tilting movement and in a predetermined position in said box. 100

7. A paint set including a plurality of rectilinear bottles having opposed vertically extending sides, a plurality of spaced outwardly extending ribs integral with the sides of each of said bottles at the approximate center of gravity thereof, a box portion, a spaced partition formed 110 of a sheet of flexible material secured to said box portion in spaced relation to the bottom of said box and having a plurality of rectilinear openings 115 therein corresponding in shape to the shape of said bottles but having slightly smaller dimensions than the outer dimensions of the said flanges, the edges of said openings being adapted to be sprung into interlocked position between the outwardly extending flanges of said bottles, thereby to maintain said bottles against tilting 120 movement and in a predetermined position in said box. 125

8. A paint set including a plurality of substantially square bottles containing different colors of liquid paints, a box, a spaced partition formed 130 of a sheet of flexible material having a plurality of substantially square openings therein secured in said box in spaced relation to the bottom thereof and extending on a line substantially parallel thereto, a pair of spaced ribs extending outwardly from the sides of each of said bottles at the 135 approximate center of gravity thereof, the said ribs being adapted to engage the opposite faces of said partition adjacent the openings therein when the edges of the openings of said partition 140 member are sprung into interlocked relation with said ribs. 145

9. A paint set including a plurality of substantially square bottles containing different colors of liquid paints, a box, a spaced partition formed 150

of a sheet of flexible material having a plurality of substantially square openings therein secured in said box in spaced relation to the bottom thereof and extending on a line substantially parallel thereto, a pair of spaced ribs extending outwardly from the sides of each of said bottles at the approximate center of gravity thereof, the said ribs being adapted to engage the opposite faces of said partition adjacent the openings therein when the edges of the openings of said partition member are sprung into interlocked relation with said ribs by movement of the bottles in a substantially vertical direction relative to said partition. 80
